UNITED STATES PATENT OFFICE.

THOMAS W. HOUCHEIN, OF NEW YORK, N. Y.

GAS-LIGHTING TORCH.

SPECIFICATION forming part of Letters Patent No. 273,085, dated February 27, 1883.

Application filed November 18, 1882. (No model.)

To all whom it may concern:

Be it known that I, THOMAS W. HOUCHEIN, of New York, in the county of New York and State of New York, have invented certain new and useful Improvements in Gas-Lighting Torches; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is an elevation of the torch. Fig. 2 is a vertical section of the key-tube. Fig. 3 is a perspective view of the taper-holder. Fig. 4 is a detail view, showing the swivel-joint in the tubes. Fig. 5 is an elevation of the taper-holder. Fig. 6 is a perspective detail, showing one method of making the flexible key-rod. Figs. 7 and 8 show some of the divergences and curvatures of the ends of the tubes and various positions into which they may be turned.

This invention relates to improvements in gas-lighting torches, and has for its object the production of a device which can be employed to light a jet or turn a cock in whatever position they may be.

The invention consists primarily in a torch having jointed taper and key tubes, and also in certain details of construction which will be hereinafter set forth.

In the annexed drawings, the letter A indicates the torch, having the main or stationary handle *a* and the taper key tubes *B* and *C*, these being firmly connected to the handle *a*, back to back, and soldered their entire contacted lengths. At the point *a'* these tubes diverge, their ends *b* and *c* having a curvature, as shown, the amount of divergence and curvature varying in different torches. Each tube has a joint, *n*, in its end *b* *c* such joint having a construction, that enables the extreme portion *b'* *c'* to be turned completely around, and to be placed at any angle with the stem portions *b* *c* of the tubes. In Fig. 4 is shown one form of joint, though various kinds may be used. On the outer end of the stem *b* is made a collar, *n'*, and below a ring, *n*², is secured, forming a recess, *n*³. The lower end, *p*, of the portion *b'* is made with a circular projection, forming an

interior annular recess, *p*'. The collar *n'* fits in this recess *p*', and the tip of the portion *b'* fits in the recess *n*³. This forms a swivel-joint capable of free rotary movement.

The taper tube *B* has on its under side an opening or slot, *m*, its entire length, except at its extreme end, where it is closed by a collar, *m'*. Within the tube *B* is the taper-holder *D*, its thumb-piece *d* projecting through the slot *m*. This holder has the shape shown in Figs. 3 and 5. It may be made of wire and bent into shape, or the jaws may be made separate and the thumb-piece be soldered thereto; but I prefer to make this of metal stamped out and struck up into shape, forming the thumb-piece *d* and the clamping-jaws *d*' *d*². One of these, *d*', is shorter than the other, so that its notched end *d*³ comes inside of the other, *d*. This holder is put in place, and the collar *m'* being fastened on keeps it from coming out. The holder *D* is run up to the end of the tube *B* until the jaws *d*' *d*² project. The end of the taper *E* is put between them, as shown in Fig. 3, and the holder is then slid inward. The jaws passing into the tube are compressed together, biting and holding the taper fast and beyond danger of being loosened.

Passing through the key-tube *C* is the key-operating rod *F*, secured at one end to the movable handle *G*, and carrying at its other end the key *H*. This rod is made flexible, so as to be adapted to the curvature of the tube *C*. It may be made with flexible joints *f* for a portion of its length, where it passes through the curved portion of the tube, or it may be made of some flexible material—such as an elastic rod, as shown in Fig. 8—as I do not propose to confine myself to any special construction. The key *H* carried by this rod is made by stamping. The key ordinarily used is made of heavy cast metal, brass or other, and is liable to break the glass shades. This key is made of wire twisted and then stamped up into the jaws *g*, or it may be made of thin sheet metal, thereby insuring lightness with strength. The stationary handle *a* is hollow, as shown, and can be used for a match-receptacle, a door, *a*², being made to give admittance.

In Figs. 7 and 8 are shown several of the positions into which the end portions, *b'* *c'*, of the taper and key tubes can be turned. These

various positions adapt the torch for various uses. The taper can be used for lighting a jet above a shade and under a shade, also when the jet is in a chandelier or a side bracket. The key 5 can be used for operating a cock either from below or at one side, and in whatever position the jet or cock may be this device can be employed.

In using this device for turning a cock the 10 portion e' is turned to the proper position so that the key H can readily grasp the cock. The handle G is thus turned in the proper direction, operating the rod and key and turning the cock.

15 - Having thus described my invention, what I claim is—

1. A gas-lighting torch jointed as described.
2. A bent gas-lighting torch having a joint in the bend, whereby its end can be turned into 20 various positions, as set forth.
3. A gas-lighting torch in which the taper or key tube, or both, is provided with a joint, whereby the device is adapted for use in whatever position the jet or cock may be, as set 25 forth.

4. In a gas-lighting torch, the key-tube, in combination with a flexible rod which passes through said tube and carries the key, as set forth.

5. The key-tube C, in combination with the 30 movable handle G, the flexible rod F, and the key H, as set forth.

6. In a gas-light torch, the operating key made of wire stamped into shape, as and for the purpose set forth. 35

7. In a gas-lighting torch, the taper-holder D, having spring-jaws d' d'' , in combination with the taper-tube, the holder resting in and adapted to slide in the said tube, whereby the spring-jaws are pressed together, as set forth.

8. The taper-holder D, having the spring-jaws d' d'' , one of which is shorter than the other, as set forth.

In testimony that I claim the foregoing as my own I affix my signature in the presence of 40 two witnesses.

THOMAS W. HOUCHIN.
